UNITED STATES PATENT OFFICE.

ALBERT P. McBRIDE, OF INDEPENDENCE, KANSAS.

CASING PACKER AND SHOE FOR GAS OR OIL WELLS.

SPECIFICATION forming part of Letters Patent No. 785,906, dated March 28, 1905.

Application filed December 6, 1904. Serial No. 235,683.

To all whom it may concern:

Be it known that I, ALBERT P. McBRIDE, a citizen of the United States, residing at Independence, in the county of Montgomery and 5 State of Kansas, have invented certain new and useful Improvements in Casing Packers and Shoes for Gas or Oil Wells, of which the following is a specification.

This invention provides novel means for 10 packing deep wells, such as oil and gas, which will obviate crowding of the packing material past the upper retainer and the consequent loss of its effectiveness after a comparatively short period of use.

15 For a full description of the invention and the merits thereof and also to acquire a knowledge of the details of construction of the means for effecting the result reference is to be had to the following description and accompanying 20 drawings.

While the invention may be adapted to different forms and conditions by changes in the structure and minor details without departing from the spirit or essential features thereof, 25 still the preferred embodiment thereof is shown in the accompanying drawings, in which—

Figure 1 is a vertical central section of a 30 casing packer and shoe embodying the invention, showing the normal arrangement of the parts. Fig. 2 is a view similar to Fig. 1, showing the relation of the parts after the casing is settled.

Corresponding and like parts are referred 35 to in the following description and indicated in both views of the drawings by the same reference characters.

The numeral 1 indicates a tubular section which is adapted to be coupled to the lower 40 end of the casing and form, in effect, a length thereof. The lower end of the section 1 is externally tapered, as shown at 2, a shoulder 3 being formed at the base of the tapered part 2. A band or collar 4 is threaded upon the 45 upper end of the section 1, and the casing is threaded therein. The lower portion of the collar or band 4 is tapered, as indicated at 5, and coöperates with an expansible ring 6, loosely fitted upon the section 1 and having 50 its upper portion flared to conform to the ta-

per 5. The ring 6 is split at 7 to provide for its expansion when forced upon the taper 5. The lower end of the ring 6 is curved outward and downward, as shown at 8, to engage with the upper end of the packing 9 and confine 55 the same. The ring 6 constitutes a retainer for the upper end of the packing 9 and is preferably made of spring material, such as steel. A second ring, 10, is loosely mounted upon the lower portion of the tubular section 1 and 60 is normally supported upon the shoulder 3 and is externally tapered, and its upper end 11 is curved in a similar manner to the end 8 of the ring 6. The ring 10 constitutes a lower retainer for the packing 9. 65

When the parts are assembled, the ring 10 is supported by the shoulder 3, and the ring 6 is prevented from upward displacement by the collar or band 4. The packing 9 is slipped upon the section 1 and is confined between the 70 rings or retainers 6 and 10 and may be of rubber or other material commonly employed for packing deep wells. The tapered end 2 constitutes a shoe and descends as the well is bored or deepened. The retainer or ring 10 75 catches upon the sides of the well and is held in place by a wedge action, and as the casing descends the packing 9 is compressed and pressing upward upon the ring or retainer 6 causes the same to ride upon the taper 5, with 80 the result that the ring 6 is expanded, so as to snugly fit the sides of the well and prevent the upper portion of the packing 9 being forced above the lower end thereof. This is indicated most clearly in Fig. 2. The expansion of the ring 6 proportionately increases the resisting-surface against which the upper 85 end of the packing 9 bears and at the same time serves to confine all of the packing which is expanded in a diametrical direction proportionate to the longitudinal compression, thereby insuring the formation of a tight joint between the casing and the sides of the well and preventing water or the like finding its way 90 into the casing. The well or opening is of 95 larger diameter than the packer, thereby permitting the latter to readily enter the well and descend to the bottom or place to be packed before operating. When the tapered ring 10 reaches the contracted point of the 100

well, its descent is arrested, and the string of casing settling forces the tapered part 5 of the collar or band 4 into the ring 6 and expands it and the packing 9.

5 Having thus described the invention, what is claimed as new is—

In combination, a tubular section having its lower end tapered and formed with an outer shoulder at the base of the taper, a band at 10 the upper end of the tubular section having its outer lower end tapered, upper and lower rings loose upon the tubular section and hav-

ing their inner or opposing ends outwardly flared, the upper ring having its inner side flared to conform to the tapered portion of the 15 aforementioned band and made expansible, and packing loose upon the tubular section and confined between the rings thereof.

In testimony whereof I affix my signature in presence of two witnesses.

ALBERT P. McBRIDE. [L. S.]
